18 Claims. (Cl. 260—293.4)

ABSTRACT OF THE DISCLOSURE

The invention is directed to compounds useful as gastric secretion inhibitors and having the formula

in which one of the radicals R₁, R₂ and R₃ stands for a monocyclic carbocyclic aryl radical and the other two stand for hydrogen, monocyclic cyclo-lower alkyl or alkenyl and/or monocyclic carbocyclic aryl, m stands for an integer from 1 to 4, n for an integer from 5 to 8, p for an integer from 2 to 8 and X for one of the groups

and

in which each of the radicals R, R' and R'' stands for hydrogen, lower alkyl or alkenyl, monocyclic cycloalkyl or cycloalkenyl, monocyclic cycloalkyl-lower alkyl or -alkenyl, monocyclic carbocyclic aryl-lower alkyl or -alkenyl or monocyclic carbocyclic aryl and acid addition salts thereof.

This is a continuation-in-part of application Ser. No. 416,144 filed Dec. 4, 1964.

The present invention concerns and has for its object the provision of N-mercaptoalkyl-alkyleneimines containing an unsaturated hydrocarbon radical in the heterocyclic ring, quaternaries and salts of these compounds, as well as methods for their preparation.

The mercaptoalkyl group of these compounds attached to the imino-nitrogen, more especially is a mercapto-lower alkyl group in which the mercapto group is separated from the imino-nitrogen by at least two carbon atoms. Its alkyl chain may be straight or branched and preferably contains 2 to 4 carbon atoms. Examples for the mercaptoalkyl group are the following: 1-mercaptopropyl-(2), -propyl-(2), -propyl-(3), -butyl-(2), -butyl-(3), -butyl-(4), -hexyl-(6), -heptyl-(5), -octyl-(4) or 2-methyl-propyl-(2); 2-mercaptopropyl-(3), -butyl-(3), -butyl-(4) or pentyl-(5); 3-mercaptopropyl-(4) or -hexyl-(6). The mercapto group thereof may be free or substituted; it preferably stands for a member selected from the group consisting of —S—R,

2

in which each of the radicals R, R' and R'' represents hydrogen or a lower aliphatic, araliphatic or aromatic hydrocarbon radical, especially lower alkyl, such as methyl, ethyl, n- or i-propyl, n-, i-, secondary- or tertiary-butyl, pentyl, hexyl or heptyl, lower alkenyl, such as allyl or methallyl, cycloalkyl or cycloalkenyl containing preferably 5 to 6 ring carbon atoms such as cyclopentyl, cyclohexyl, cyclopentenyl or cyclohexenyl, cycloalkyl-lower alkyl or -alkenyl containing preferably 5 to 6 ring carbon atoms, such as

10 cyclopentylethyl, cyclohexylmethyl or cyclopentylallyl, aryl-lower alkyl or -alkenyl, especially monocyclic carbocyclic aryl-lower alkyl or -alkenyl, such as benzyl, phenethyl-(1) or -(2) or cinnamyl or monocyclic carbocyclic aryl. These hydrocarbon radicals may be unsubstituted or substituted, especially in the aromatic part, by one or more than one of the same or of different substituents, such as lower alkyl, e.g. methyl ethyl, n- or i-propyl, free or etherified hydroxy or mercapto, e.g. methoxy, ethoxy or methylenedioxy, methyl- or ethylmercapto, halogen, e.g. fluoro, chloro or bromo, trifluoromethyl, nitro or amino, for example, lower alkyl- or di-lower alkylamino, e.g. methylamino, ethylamino, dimethylamino, diethylamino or methylethylamino.

The alkyleneimino ring of the compounds of this invention, more especially contains a straight or branched alkylene group and having from 3 to 8 ring carbon atoms. Above all, it represents piperidino, but also pyrrolidino, 1,5-, 1,6- or 2,5 - hexamethyleneimino, 1,5-, 1,6-, 1,7- or 2,6 - heptamethyleneimino or 1,8-, 3,6- or 3,7-octamethyleneimino.

The unsaturated hydrocarbon radical attached to any of the ring carbon atoms of the alkyleneimino ring available for substitution above all is an aralkyl, cycloalkyl- or cycloalkenylaralkyl or a partially hydrogenated aryl radical. More especially it is a lower alkyl group containing one to three monocyclic, carbocyclic aryl radicals, such as benzyl, diphenylmethyl (benzhydryl), triphenylmethyl, phenethyl-(1) or -(2), 1,1- or 1,2- diphenylethyl, 1,1,1 - triphenylethyl-(2), phenylpropyl-(1), (2) or -(3), 1,1-, 2,2-, 3,3-, 1,2-, 1,3- or 2,3-diphenylpropyl-(3), 1,3 - diphenylpropyl-(2), 1,2,3 - triphenylpropyl-(2), phenylbutyl-(1), -(2), -(3) or -(4), 1,1-, 2,2-, 1,3-, or 2,3-diphenylbutyl-(3) or -(4) or tribenzylmethyl; or a lower alkyl group containing at least one cyclo-lower alkyl or alkenyl group, containing preferably 5 or 6 ring carbon atoms, and at least one monocyclic carbocyclic aryl radical, but containing not more than 3 cyclic radicals, such as α -cyclopentyl-, α -cyclohexyl- or α -cyclohexen - (2) - yl-benzyl, α - or β -cyclohexyl-phenethyl-(2) or 1-cyclopentyl- or 1-cyclopenten-(2)-yl-2,2-diphenylethyl-(2); or a partially hydrogenated bi- or tricyclic carbocyclic aryl radical, such as indenyl-(1), hydroindenyl-(2), tetralinyl-(1) or -(2), fluorenyl-(9), acenaphthetyl-(1), 9,10 - dihydro-anthrazenyl - (9) or 1,2,3 - trihydrophenalenyl - (2). These hydrocarbon radicals may be unsubstituted or substituted, especially in the aromatic part, by one or more than one of the same or of different substituents, such as those mentioned for R.

45 60 The new compounds possess valuable pharmacological properties. For example, they cause a marked decrease of the gastric secretion, especially of gastric hydrochloric acid, which can be demonstrated, for example, at a dosage range between about 1-15 mg./kg./day, preferably 5-10 mg./kg./day, on the dog, of which the gastric secretion is induced either by food or by parenteral application of histamine. The compounds of this invention, are therefore, useful in the management and treatment of 65 70 gastric irritation or of gastric ulcers by reducing the amount of free acid in the stomach. They are also useful as research tools in the study of the releasing mech-

anism of the gastric secretion. Furthermore, the new compounds are useful starting materials or intermediates in the manufacture of other valuable compounds, especially medicines.

Particularly useful are compounds of the general formula:

in which one of the radicals R_1 , R_2 and R_3 stands for a monocyclic carbocyclic aryl radical and the other two stand for hydrogen, monocyclic cyclo-lower alkyl or alkenyl and/or monocyclic carbocyclic aryl, m stands for an integer from 1 to 4, n for an integer from 5 to 8, p for an integer from 2 to 8 and X for one of the groups

and

in which each of the radicals R , R' and R'' stands for hydrogen, lower alkyl or alkenyl, monocyclic cycloalkyl or cycloalkenyl, monocyclic cycloalkyl-lower alkyl or alkenyl, monocyclic carbocyclic aryl-lower alkyl or alkenyl or monocyclic carbocyclic aryl, and acid addition salts thereof.

Compounds that are especially valuable are those of the formula:

in which each of the groups R_4 and R_5 stands for phenyl, lower alkyl-phenyl, lower alkoxy-phenyl, halophenyl, trifluoromethylphenyl or di-lower alkylamino-phenyl, each of the groups R_6 and R_7 stands for hydrogen or lower alkyl and q stands for an integer from 2 to 4, and acid addition salts thereof.

Above all, the present invention concerns compounds of the formula:

in which R_4 , R_5 and q have the meaning given above, and acid addition salts thereof.

The new compounds are prepared by methods in themselves known. For example, the procedure is

(a) To replace in an $N-(R_o\text{-alkyl})\text{-alkyleneimine}$, containing in the ring an unsaturated hydrocarbon radical, the substituent R_o , capable of being converted into mercapto, by a free or substituted mercapto group or

(b) To add a compound, containing a free mercapto group, to an $N\text{-alkenyl-alkyleneimine}$ containing in the ring an unsaturated hydrocarbon radical or

(c) To react an $N\text{-unsubstituted alkyleneimine}$, containing in the ring an unsaturated hydrocarbon radical, with a reactive O-esterified mercapto-alkanol or

(d) To reduce in an $N\text{-mercaptoalkyl-alkyleneimine}$ containing in the ring an unsaturated hydrocarbon radical and in the ring and/or alkyl chain at least one carbamyl or ethylene grouping, said grouping to the

5 methyleneimino or ethylene grouping respectively, and, if desired, converting the final products into each other, converting a resulting free compound into a salt or quaternary ammonium compound or converting a resulting salt into the free compound or into another salt.

10 The substituent R_o capable of being converted into mercapto represents, for example, esterified hydroxy, preferably halogeno, e.g. chloro, bromo, or iodo, or aliphatic or aromatic sulfonyloxy, such as methane-, ethane-, benzene- or p-toluene-sulfonyloxy. The $N-(R_o\text{-alkyl})\text{-alkyleneimine}$ starting compounds may be reacted with a compound containing a free mercapto group, such as hydrogen sulfide, a thio-alcohol or thiophenol, thiocyanic acid, a mono- or dithiocarbamic acid, an ester thereof or a thiourea containing at least one hydrogen atom, or advantageously a metal salt thereof, especially an alkali metal, e.g. sodium or potassium salt thereof.

15 A reactive O-esterified mercapto-alkanol is, for example, a halo- or sulfonyloxy-alkane containing preferably a substituted mercapto group, which is separated from the halogen, e.g. chloro or bromo atom or the sulfonyloxy, e.g. p-toluene sulfonyloxy group, by at least two carbon atoms.

20 In the $N\text{-mercaptoalkyl-alkyleneimine}$ starting compounds in which a carbonyl group is connected with the imino nitrogen atom (i.e. forming a carbamyl group), the carbonyl group can be reduced, for example, with a complex light metal hydride, e.g. lithium aluminum hydride. Said starting compounds that contain a double bond, (or ethylene grouping respectively) it preferably extends from the ring carbon atom that carries the unsaturated hydrocarbon radical, may be reduced with catalytically activated hydrogen, e.g. hydrogen in the presence of a palladium catalyst.

25 The final products of this invention may be converted into each other by methods in themselves known. Thus, for example, a compound obtained containing the free mercapto group can be reacted with a reactive esterified lower aliphatic or araliphatic alcohol, e.g. a lower 30 alkyl halogenide or sulfate, an aromatic diazonium compound, e.g. benzene diazonium chloride, a lower aliphatic or araliphatic hydrocarbon containing an olefinic double bond, e.g. ethylene, cyclopentene or styrene, a halocyan, e.g. bromocyan, an isocyanate or thioisocyanate, a carbamic or thiocarbamic acid halide or a cyanamide, in order to obtain the hereinbefore described compounds containing a substituted mercapto group. Furthermore the amidino-mercaptanes (isothioureas) obtained may be hydrolyzed, for example, with aqueous alkali metal hydroxides in order to obtain the unsubstituted mercaptanes, the cyano-mercaptanes (rhodanides) 35 may be additively combined with water, hydrogen sulfide, alcohols or thiols, preferably under acidic conditions, e.g. in the presence of hydrochloric acid, or carbamyl- or thiocarbamyl-mercaptanes (thio- or dithiouethanes) with aliphatic or araliphatic halogenides. The quaternaries are obtained from the free compounds by reacting them preferably with reactively esterified lower alkanols.

40 The above mentioned reactions are carried out according to standard methods, in the presence or absence of diluents, preferably such as are inert to the reagents and are solvents thereof, of catalysts, condensing agents and/or of inert atmospheres, at atmospheric or superatmospheric pressure, at low temperatures, room temperature or elevated temperatures. Condensing agents are preferably used in the reaction of compounds with a reactive esterified hydroxy group whereby an acid is split off. They are especially inorganic or organic bases, for example, alkali metal carbonates, such as potassium carbonate, or tertiary nitrogen bases, such as trimethylamine or pyridine.

45 The end products are obtained in the free form or in the form of their salts, depending on the conditions under which the process is carried out; the salts are also included in the present invention. Salts that are obtained

can be converted into the free bases in known manner, for example, with alkalis or ion exchangers. Free bases that are obtained can be converted into salts by reaction with organic or inorganic acids, especially those that are suitable for the formation of therapeutically useful salts. Such acids are, for example, hydrohalic acids, e.g. hydrochloric or hydrobromic acid, sulfuric, phosphoric, nitric or perchloric acid, aliphatic, alicyclic, araliphatic, aromatic or heterocyclic carboxylic or sulfonic acids, for example, formic, acetic, propionic, succinic, glycollic, lactic, malic, citric, ascorbic, maleic, hydroxymaleic, pyroracemic, phenylacetic, benzoic, aminobenzoic, anthranilic, hydroxybenzoic, salicylic, aminosalicylic, embonic, nicotinic, methanesulfonic, ethanesulfonic, hydroxyethanesulfonic, ethylenesulfonic, halogenobenzene-sulfonic, toluenesulfonic, naphthalenesulfonic and sulfanilic acid; methionine, tryptophan, lysine and arginine.

These and other salts of the new compounds, for example, the picrates, can also be used for purification of the bases obtained; the bases are converted into salts, the salts are separated and the bases are liberated from the salts. In view of the close relationship between the free compounds and the compounds in the form of their salts, whenever a free base is referred to in this context, a corresponding salt is also intended, provided such is possible or appropriate under the circumstances.

The invention further includes any variant of the present process, in which an intermediate product obtainable at any stage of the process is used as starting material and any remaining steps are carried out, or the process is discontinued at any stage thereof, or in which the starting materials are formed under the reaction conditions, or in which the reaction components may be used in the form of their salts.

Mainly, those starting materials should be used in the reactions of the invention that lead to the formation of those compounds indicated above as being especially valuable.

The starting materials are known, or if they are new, may be prepared by methods in themselves known. Several of the new starting materials are described in our copending applications Ser. No. 392,931, filed Aug. 28, 1964, U.S. Patent No. 3,252,983, Ser. No. 416,154, filed Dec. 4, 1964 (now abandoned) and Ser. No. 480,147 filed Aug. 16, 1965, now abandoned.

The N-mercaptopalkyl-alkyleneimino starting compounds, containing at least one carbamyl or ethylene group, may be prepared analogous to the method described under (a) and (c) by selecting the appropriate reagents, for example, by reaction of an N-haloalkyl-alkyleneimine or oxoalkyleneimine containing in the ring an unsaturated hydrocarbon radical, with a compound containing a free mercapto group, e.g. those mentioned above or by reaction of a corresponding N-unsubstituted alkenyleneimine or oxoalkyleneimine with a haloalkylmercapto compound or by reaction of a corresponding N-unsubstituted alkyleneimine or alkenyleneimine with a mercapto-alkanoyl halide.

Starting materials or final products that are mixtures of isomers may be separated into single isomers by methods in themselves known. For example, compounds that contain one or more asymmetrical carbon atoms may be in the form of racemate mixtures, pure racemates or optical antipodes.

Mixtures of racemates, by virtue of the physicochemical differences between the components, can be resolved into the stereoisomeric pure racemates (diastereoisomers), for example, by chromatography and/or fractional crystallization. Racemic products can likewise be resolved into the optical antipodes, for example, by reaction with optically active acids, separation of the diastereomeric salts and liberation of the bases from the salts.

The new compounds can be used in the free form or in the form of their salts, for example, for the manufacture of pharmaceutical preparations containing the said com-

pounds in admixture with organic or inorganic, solid or liquid pharmaceutical excipients suitable especially for enteral but also for parenteral administration. Suitable excipients are substances that do not react with the new compounds, for example, water, gelatine, lactose, starch, stearyl alcohol, magnesium stearate, talc, vegetable oils, benzyl alcohols, gums, propylene glycols, white petroleum jelly and other known medicinal excipients. The pharmaceutical preparations may be, for example, tablets, dragees or capsules, or in liquid form as solutions, suspensions, or emulsions. They may be sterilized and/or contain adjuvants, such as preserving, stabilizing, wetting or emulsifying agents, solution promoters, salts for regulating the osmotic pressure or buffers. They may further contain other therapeutically valuable substances. The pharmaceutical preparations are prepared by conventional methods.

The following examples illustrate the invention, temperatures are given in degrees centigrade and all parts given are parts by weight.

Example 1

The solution of 3.55 g. of N-(2-chloro-ethyl)-3-benzhydryl-piperidine hydrochloride in 50 ml. of ethanol is added with stirring to a solution of 0.86 g. of thiourea in 25 ml. of ethanol and the mixture refluxed for 6 hours. Thereupon it is concentrated under reduced pressure, the residue triturated with ether and the whole filtrated. The filter residue is recrystallized from ethanol-ether in order to obtain the pure N-(2-guanylmercapto-ethyl)-3-benzhydryl-piperidine hydrochloride of the formula:

melting at 195-208°.

Example 2

The suspension of 25.1 g. of 3-benzhydryl-piperidine, 11.0 g. of β -chloroethyl-methylsulfide, 15.0 g. of sodium carbonate in 250 ml. of butanol containing a trace of water, is refluxed with stirring for 24 hours. After cooling the reaction mixture is filtered, the filtrate concentrated under reduced pressure and the residue distilled in a high vacuum. There is obtained the N-(2-methylmercapto-ethyl)-3-benzhydryl-piperidine of the formula:

Example 3

To the suspension of 3.9 g. of N-(2-guanylmercapto-ethyl)-3-benzhydryl-piperidine hydrochloride in 10 ml. of water the solution of 8.1 g. of sodium hydroxide in 30 ml. of water is added with stirring and stirring is continued for 5 hours at room temperature. Thereupon the reaction mixture is saturated with sodium chloride, extracted with diethyl ether and the extract concentrated in vacuo in a stream of nitrogen. The residue represents the N-(2-mercaptop-ethyl)-3-benzhydryl-piperidine of the formula:

Example 4

The boiling solution containing 25.0 g. of N-allyl-3-benzhydryl-piperidine and a trace of benzoyl peroxide in 120 ml. of benzene is treated with methyl mercaptan for 24 hours. After concentration of the reaction mixture under reduced pressure and distillation of the residue in a

high vacuum, there is obtained the N-(3-methyl mercapto-propyl)-3-benzhydryl-piperidine of the formula

Example 5

Other compounds of this invention which are prepared according to the above described and illustrated procedure by selecting equivalent amounts of the appropriate starting materials are, for example, the following:

8
gradually adding 4,000 ml. of boiling purified water. The mixed powders are granulated with the above paste, using additional water as required.

The resulting moist mass is passed through a mill, using a No. 4A screen, placed on trays and dried at 38° C. until the moisture content is between 2 percent and 3 percent. The granules are broken on a mill, passed through a No. 16 screen, and treated with the stearic acid and the calcium stearate, both screened through a No. 20 screen. After mixing for twenty minutes, the granulation is compressed into tablets, each weighing 0.25 g., using 1 1/2 inch dies, standard concave punches, uppers bisected, lowers monogrammed.

Starting Material	Reagent	Final Product
N-(2-chloro-ethyl)-2-benzhydryl-piperidine hydrochloride.	Thiourea.....	N-(2-guanylmercapto-ethyl)-2-benzhydryl-piperidine hydrochloride.
N-(2-chloro-ethyl)-4-benzhydryl-piperidine hydrochloride.	.....do.....	N-(2-guanylmercapto-ethyl)-4-benzhydryl-piperidine hydrochloride.
N-(3-chloro-propyl)-3-(di-paratolyl-methyl)-piperidine hydrochloride.	.....do.....	N-(3-guanylmercapto-propyl)-3-(di-paratolyl-methyl)-piperidine hydrochloride.
N-(2-chloro-ethyl)-3-(di-para chlorophenyl-methyl)-piperidine.	Potassium thiocyanate.....	N-(2-cyanomercapto-ethyl)-3-(di-para chlorophenyl-methyl)-piperidine.
N-(2-chloro-ethyl)-3-(<i>o</i> -cyclohexyl-benzyl)-piperidine hydrochloride.	N,N'-diethyl-thiourea.....	N-(2-(N,N'-diethyl guanylmercapto)-ethyl)-3-(<i>o</i> -cyclohexyl-benzyl)-piperidine hydrochloride.
N-(2-chloro-ethyl)-3-(<i>o</i> -cyclohexyl-benzyl)-piperidine hydrochloride.	γ-Bromopropyl-benzylsulfide.....	N-(3-benzylmercapto-propyl)-3-(di-para methoxy-phenyl-methyl)-piperidine.
3-(di-para methoxy-phenyl-methyl)-piperidine.....	β-chloroethyl-phenylsulfide.....	N-(2-phenylmercapto-ethyl)-3-fluorenyl-(9)-piperidine.
3-fluorenyl-(9)-piperidine.....	N,N-dimethyl-thiourea.....	N-[2-(N,N-dimethyl guanylmercapto)-ethyl]-3-(<i>o</i> -para fluorophenyl-benzyl)-piperidine hydrochloride.
N-(2-chloro-ethyl)-3-(<i>o</i> -para-fluoro-phenyl-benzyl)-piperidine hydrochloride.	Thiourethane.....	S-[2-(3-benzhydryl-piperidino)-ethyl]-thiourethane hydrochloride.
N-(2-chloro-ethyl)-3-benzhydryl-piperidine.....	β-chloroethyl-cyclohexylsulfide.....	N-(2-cyclohexylmercapto-ethyl)-3-(1,2-diphenyl-ethyl)-piperidine.
3-(1,2-diphenyl-ethyl)-piperidine.....	β-chloropropyl-ethylsulfide.....	N-(3-ethylmercapto-propyl)-3-(di-ortho methoxy-phenyl-methyl)-piperidine.
3-(di-ortho methoxy phenyl-methyl)-piperidine.....	Thiourea.....	N-(3-guanylmercapto-propyl)-3-(di-para di-ethyl-aminophenyl-methyl)-piperidine hydrobromide.
N-(3-bromo-propyl)-3-(di-para diethylamino-phenyl-methyl)-piperidine.	.....do.....	N-(2-guanylmercapto-ethyl)-3-triphenyl-methyl-piperidine hydrobromide.
N-(2-bromo-ethyl)-3-triphenyl-methyl-piperidine.....	3-bromo-2-methyl-propyl-cyclopentylmethyl-sulfide.....	N-(3-cyclopentylmethyl-mercapto-2-methyl-propyl)-3-benzyl-piperidine.

N-methallyl-3-benzhydryl-piperidine.....	.....do.....	N-(2-methylmercapto-3-methyl-butyl)-3-benzhydryl-piperidine.
N-(3-methyl-butene-(2)-yl)-3-benzhydryl-piperidine.....		

Example 6

Preparation of 500 capsules each containing 0.01 g. of the active ingredient.

Ingredients:	G. 45
N-(2-guanylmercapto-ethyl)-3-benzhydryl-piperidine hydrochloride	5.000
Lactose	85.000

PROCEDURE

The ingredients are blended in a suitable mixer, sieved through a No. 40 screen and again mixed; portions weighing 0.18 g. each of the resulting mixture are filled into No. 4 capsules.

Example 7

Preparation of 160,000 tablets each containing 0.025 g. of the active ingredient.

Ingredients:	G.
N-(2-guanylmercapto-ethyl)-3-benzhydryl-piperidine hydrochloride	4,000.0
Lactose	28,289.0
Corn starch	3,410.0
Confectioners sugar	2,800.0
Colloidal silica	1,000.0
Stearic acid powder	400.0
Calcium stearate	100.0
Color F D & C yellow No. 5	1.0
Purified water, q.s.	

PROCEDURE

The hydrochloride, the lactose, 2,500 g. of the corn starch, the confectioners sugar and the colloidal silica are passed through a No. 16 screen into a mixer and blended at low speed for twenty minutes. The remainder of the corn starch is suspended in a cold solution of the color in 1,000 ml. of purified water, and a paste is formed by

Example 8

The mixture of 10.0 g. 3-benzhydryl-piperidine, 8.62 g. 2-phenylmercapto-ethyl bromide, 15.0 g. sodium carbonate, 1 drop water and 100 ml. benzene is refluxed for 6 hours while stirring. Hereupon it is filtered, the filtrate concentrated and the crystals, separating on standing in the cold are filtered off. The so-obtained N-(2-phenylmercapto-ethyl)-3-benzhydryl-piperidine of the formula

55 is recrystallized from ethanol and melts at 99–100°.

50

To the solution of 3.5 g. N-(2-chloroethyl)-3-benzhydryl-piperidine hydrochloride in 50 ml. absolute ethanol, the solution of 1.14 g. N,N-dimethyl-thiourea in 30 ml. absolute ethanol is added and the whole refluxed for 6 hours while stirring, and stirring is continued overnight at room temperature. The reaction mixture is concentrated in vacuo and the residue recrystallized from ethanol-diethyl ether to yield the N-[2-(N,N-dimethyl-guanylmercapto)-ethyl]-3-benzhydryl-piperidine dihydrochloride of the formula

70 75 which melts after drying in a high vacuum at 149–153°.

9

The analogously prepared N-[2-(N,N-diethyl-guanylmercapto)-ethyl]-3-benzhydryl-piperidine dihydrochloride melts at 58-59° (at 119° clear melt).

Example 10

To the stirred solution of 1.15 g. N-ethyl-thiourea in 35 ml. anhydrous ethanol, the solution of 3.5 g. N-(2-chloro-ethyl)-3-benzhydryl-piperidine hydrochloride in 50 ml. anhydrous ethanol is added and the whole is refluxed for 6 hours and stirred at room temperature overnight. The reaction mixture is evaporated in vacuo, the residue recrystallized from ethanol-diethyl ether to yield N-[2-(N-ethyl-guanylmercapto)-ethyl]-3-benzhydryl-piperidine dihydrochloride of the formula

melting at 86-90°.

Example 11

To the solution of 1.32 g. N,N'-diethyl-thiourea in 35 ml. absolute ethanol, the solution of 3.5 g. N-(2-chloro-ethyl)-3-benzhydryl-piperidine hydrochloride in 50 ml. absolute ethanol is added while stirring and the mixture is refluxed for 6 hours and stirred overnight at room temperature. Hereupon, it is evaporated under reduced pressure; the residue triturated with diethyl ether; the ether decanted off and the residue dried in a high vacuum. There is obtained the hygroscopic N-[2-(N,N'-diethyl-guanylmercapto)-ethyl]-3-benzhydryl-piperidine dihydrochloride of the formula

In the analogous manner, the N-[2-(N,N'-diallyl-guanylmercapto)-ethyl]-3-benzhydryl-piperidine dihydrochloride is prepared from the equivalent amounts of starting materials; it melts at 65° and has the following formula

Example 12

The stirred mixture of 3.5 g. N-(2-chloroethyl)-3-benzhydryl-piperidine hydrochloride, 1.52 g. N-phenyl-thiourea and 100 ml. anhydrous ethanol is refluxed for 6 hours and stirred overnight at room temperature. The mixture is evaporated in vacuo and the residue triturated with diethyl ether to yield the N-[2-(N-phenyl-guanylmercapto)-ethyl]-3-benzhydryl-piperidine dihydrochloride of the formula

melting at 90-100°.

10

Example 13

The stirred mixture of 2.82 g. N,N'-dibenzyl-thiourea, 3.5 g. N-(2-chloroethyl)-3-benzhydryl-piperidine hydrochloride and 275 ml. anhydrous ethanol is refluxed for 6 hours, and stirring is continued at room temperature overnight. It is evaporated in vacuo and the residue recrystallized from anhydrous ethanol to yield the N-[2-(N,N'-dibenzyl-guanylmercapto)-ethyl]-3-benzhydryl-piperidine dihydrochloride of the formula

melting at 150-155°.

Example 14

The stirred mixture of 4.0 g. N-(2-chloroethyl)-3-(di-p-tolyl-methyl)-piperidine, 0.865 g. thiourea and 80 ml. anhydrous ethanol is refluxed and stirred for 8 hours and left stirring overnight at room temperature. It is evaporated in vacuo, the residue recrystallized from ethanol-diethyl ether and dried in a high vacuum to yield the hygroscopic N-(2-guanylmercapto-ethyl)-3-(di-p-tolyl-methyl)-piperidine dihydrochloride of the formula

By replacing in the above example the thiourea by 1.37 g. N-allyl-thiourea, the N-[2-(N-allyl-guanylmercapto)-ethyl]-3-(di-p-tolyl-methyl)piperidine dihydrochloride to the formula

is obtained.

Example 15

The mixture of 3.5 g. N-(2-chloroethyl)-2-(2,2-diphenyl-ethyl)-piperidine hydrochloride, 2.94 g. N,N-dimethyl-thiourea and 80 ml. absolute ethanol is refluxed for 6 hours while stirring. It is evaporated in vacuo and the residue triturated with diethyl ether to yield the N-[2-(N,N-dimethyl-guanylmercapto)-ethyl]-2-(2,2-diphenyl-ethyl)-piperidine dihydrochloride of the formula

melting at 60°.

Example 16

The stirred mixture of 4.0 g. N-(2-chloroethyl)-4-benzhydryl-piperidine hydrochloride, 0.95 g. thiourea and 80 ml. absolute ethanol is refluxed for 8 hours and stirred overnight at room temperature. It is evaporated under reduced pressure, the residue triturated with diethyl ether and the hygroscopic crystals dried in a high vacuum, to yield the N-(2-guanylmercapto-ethyl)-4-benzhydryl-piperidine dihydrochloride of the formula

11
Example 17

The mixture of 4.0 g. N-(2-chloroethyl)-4-benzhydryl-piperidine hydrochloride, 1.47 g. N-allyl-thiourea and 80 ml. anhydrous ethanol is refluxed for 6 hours while stirring and kept at room temperature overnight. It is evaporated in vacuo, the residue triturated with petroleum ether and the crystals formed are filtered off, representing the N-[2-(N-allyl-guanylmercapto)-ethyl]-4-benzhydryl-piperidine dihydrochloride monohydrate of the formula

which is very hygroscopic.

In the analogous manner, the N-[2-(N-methyl-N-phenyl-guanylmercapto)-ethyl]-4-benzhydryl-piperidine dihydrochloride of the formula

is prepared by substituting the N-allyl-thiourea by 2.07 g. N-methyl-N-phenyl-thiourea.

Example 18

The mixture of 4.0 g. 2-(2-chloroethyl)-3-(di-p-tolylmethyl)-piperidine hydrochloride, 1.52 g. N-ethyl-thiourea and 80 ml. anhydrous ethanol is refluxed for 8 hours while stirring and kept overnight at room temperature. It is evaporated in vacuo, the residue recrystallized from ethanol-diethyl ether and dried in a high vacuum to yield the hygroscopic N-[2-(N-ethyl-guanylmercapto)-ethyl]-3-(di-p-tolylmethyl)-piperidine dihydrochloride of the formula

The compounds of the present invention, mentioned in this and in previous examples, without melting or boiling point, are either too hygroscopic for estimating the M.P. or not distillable; they do, however, analyze correctly.

What is claimed is:

1. A member selected from the group consisting of compounds having the formula:

in which one of the radicals R₁, R₂ and R₃ stands for a R₄-phenyl radical and the other two stand for a member selected from the group consisting of hydrogen, monocyclic cyclo-lower alkyl, monocyclic cyclo-lower alkenyl and R₄-phenyl, and R₄ stands for a member selected from the group consisting of hydrogen, lower alkyl, lower alkoxy, halogeno, trifluoromethyl and di-lower alkylamino, m stands for an integer from 1 to 4, n for an integer from 5 to 8, p for an integer from 2 to 8 and each of the radicals R, R' and R'' stands for a member selected from the group consisting of hydrogen, lower alkyl, lower alkenyl, monocyclic cyclo-lower alkyl, monocyclic cyclo-lower alkenyl, monocyclic cyclo-lower alkyl-lower alkyl, monocyclic cyclo-lower alkyl-lower alkenyl, R₄-phenyl-lower alkyl, R₄-phenyl-lower alkenyl and monocyclic carbocyclic aryl and acid addition salts thereof.

12

2. A member selected from the group consisting of compounds having the formula:

in which each of the groups R₄ and R₅ stands for a member selected from the group consisting of phenyl, lower alkyl-phenyl, lower alkoxy-phenyl, halophenyl, trifluoromethyl-phenyl and di-lower alkylamino-phenyl, each of the groups R₆ and R₇ stands for a member selected from the group consisting of hydrogen and lower alkyl and q stands for an integer from 2 to 4 and therapeutically acceptable acid addition salts thereof.

3. A member selected from the group consisting of compounds having the formula:

in which each of the groups R₄ and R₅ stands for a member selected from the group consisting of phenyl, lower alkyl-phenyl, lower alkoxy-phenyl, halophenyl, trifluoromethyl-phenyl and di-lower alkylamino-phenyl and q stands for an integer from 2 to 4 and therapeutically acceptable acid addition salts thereof.

4. N-(2-guanylmercapto-ethyl)-3-benzhydryl-piperidine.

5. N-[2-(N,N-dimethyl-guanylmercapto)-ethyl]-3-benzhydryl-piperidine.

6. N-[2-(N,N-diethylguanylmercapto)-ethyl]-3-benzhydryl-piperidine.

7. N-[2-(N-ethyl-guanylmercapto)-ethyl]-3-benzhydryl-piperidine.

8. N-[2-(N,N-diethyl-guanylmercapto)-ethyl]-3-benzhydryl-piperidine.

9. N-[2-(N,N-diallyl-guanylmercapto)-ethyl]-3-benzhydryl-piperidine.

10. N-[2-(N-phenyl-guanylmercapto)-ethyl]-3-benzhydryl-piperidine.

11. N-[2-(N,N-dibenzyl-guanylmercapto)-ethyl]-3-benzhydryl-piperidine.

12. N-(2-guanylmercapto-ethyl)-3-(di-p-tolylmethyl)-piperidine.

13. N-[2-(N-allyl-guanylmercapto)-ethyl]-3-(di-p-tolylmethyl)-piperidine.

14. N-[2-(N,N-dimethyl-guanylmercapto)-ethyl]-2-(2,2-diphenyl-ethyl)-piperidine.

15. N-(2-guanylmercapto-ethyl)-4-benzhydryl-piperidine.

16. N-[2-(N-allyl-guanylmercapto)-ethyl]-4-benzhydryl-piperidine.

17. N-[2-(N-methyl-N-phenyl-guanylmercapto-ethyl)-4-benzhydryl-piperidine.

18. N-[2-(N-ethyl-guanylmercapto)-ethyl]-3-(di-p-tolylmethyl)-piperidine.

UNITED STATES PATENT OFFICE
CERTIFICATE OF CORRECTION

Patent No. 3,366,637

January 30, 1968

Robert Paul Mull et al.

It is certified that error appears in the above identified patent and that said Letters Patent are hereby corrected as shown below:

Column 12, lines 19 to 25, the formula should appear as shown below:

same column 12, line 40, "N-[2(N,N'-" should read -- N-[2-(N,N'- --.

Signed and sealed this 3rd day of February 1970.
